UNITED STATES PATENT OFFICE.

FRANK L. GESFORD, OF ALTURAS, CALIFORNIA.

REST ATTACHMENT FOR SAXOPHONES.

Application filed March 15, 1927. Serial No. 175,575

This invention relates to saxophone attachments and more particularly to a rest attachment for a saxophone. It is well known to players of E flat, B flat, and C melody saxophones that the contact of the key rods at the lower inner side of the instrument with the clothing frequently interferes with freedom of movement of these rods. Therefore it is the primary object of the present invention to provide a rest which may be readily adapted to any of the types of saxophones referred to and which will effectually prevent such contact of the key rods with the clothing of the player.

The invention contemplates a rest attachment for the purpose stated embodying attaching members which are applicable to the guard bridges which are arranged over the valves of certain of the openings of the instrument, and inasmuch as in the type of saxophones mentioned above the guard bridges to which the attachment will be applied are somewhat differently relatively positioned, the invention has as a further object to so construct the attaching means for the rest that this means may be readily and quickly adjusted so as to render the rest instantly applicable to any of the types of saxophones referred to, the attaching means, when once adjusted, permitting of instantaneous removal and application of the rest from and to the instrument so that when the instrument is not in use the rest may be carried in the bell of the instrument where it will be readily accessible for use when needed, or otherwise carried so that the instrument may be arranged in its carrying case without any interference on the part of the attachment.

Another object of the invention is to so construct the attaching means for the rest that when once adjusted to coact with the guard bridges of any one of the instruments, further adjustment will be unnecessary and application of the rest to and its detachment from the instrument may be effected without the employment of any tools whatsoever.

Another object of the invention is to so construct the attaching means for the rest that when the means is bodily engaged with the guard bridges it will securely hold the rest against displacement in any direction whatsoever so that the rest is as firmly and rigidly connected with the instrument as if it were an integral part thereof.

In the accompanying drawings:

Fig. 1 is a view in side elevation of the rest

attachment embodying the invention applied to a C melody saxophone, the saxophone being shown in broken lines so as to more clearly distinguish the invention;

Fig. 2 is a horizontal section on the line 2—2 of Fig. 1 looking in the direction indicated by the arrows, the instrument being shown in broken lines and the attachment being shown in top plan;

Fig. 3 is a perspective view of one of the attaching members for the rest;

Fig. 4 is a vertical transverse sectional view taken substantially on the line 4—4 of Fig. 1 looking in the direction indicated by the arrows;

Fig. 5 is a perspective view illustrating the other clip member of the attachment;

Fig. 6 is a view similar to Fig. 1 illustrating a modification of the invention as applied to an E flat saxophone;

Fig. 7 is a view in elevation of the attachment looking at the inner side thereof;

Fig. 8 is a similar view illustrating one of the attaching members.

In the embodiment of the invention illustrated in Figures 1 to 4 inclusive and in which embodiment the rest attachment is shown as adjusted for application to a C melody saxophone, the horn of the instrument is indicated in general by the numeral 1, the down branch being indicated by the numeral 2, the up branch by the numeral 3, and certain of the valves by the numerals 4 and 5, these valves controlling the openings which are lowermost in the branches 2 and 3 respectively, in this type of saxophone. As is customary in connection with each valve there is provided a guard bridge, and each bridge includes side members 6 which are permanently secured to the respective branch of the instrument and which are connected by a cross member 7, the cross member 7 having a right angular extension 8 leading therefrom and provided with a bracing portion 9 likewise permanently connected with the respective branch of the instrument. In other words the guard bridges are substantially T-shape and are symmetrically arranged with respect to the respective valves 4 and 5. The valves have connected with them the usual stems 10 and 11 respectively which stems extend from the valve operating rods 12 and 13 respectively. As previously explained it frequently happens that the rod or the valve stems or even the valves themselves come in contact with the clothing of the player with the result

that freedom of movement of the valves is interfered with and therefore the present invention contemplates the provision of a rest attachment applicable to the guard bridges for the valves and so constructed as to preclude any contact of the valve parts with the clothing of the player so that the valve may be caused to function without interference.

In the specific embodiment shown in the said Figures 1 to 4 inclusive, the rest consists essentially of a body member which is indicated by the numeral 14 and this body member may be made of wood, metal, hard rubber, bakelite, or any other material found suitable for the purpose. The rest member is preferably of the elongated form shown most clearly in Figure 1, having parallel upper and lower edges and having its ends rounded on elliptical curves. It will be observed by reference to Figures 1, 2 and 4 of the drawings that the inner surface of the body member of the rest or in other words the surface which is presented towards the instrument when the rest is in position, is flat but that the outer surface of the rest or in other words the surface which is to contact the clothing of the player is rounded in a vertical direction as best shown in Figure 4 and likewise longitudinally rounded at its ends as best shown in Figure 2 so that a smooth rounded surface is presented to the clothing of the player and there are no sharp edges or projections to come in contact with the clothing and interfere with any movement of the rest with respect to the player of the instrument, so that the player is not concerned with the position in which the rest engages his clothing but may attend fully to the playing of the instrument and remain satisfied that the rest will perform its function under all conditions.

The attaching means for the rest body 14 comprises two attaching clips arranged at the ends of the flat inner face of the rest body, and means for adjustably mounting the clips in place upon the said body. One of the attaching members or clips, which is best shown in Figure 5 of the drawings, is indicated in general by the numeral 15 and the same is preferably formed from a sheet metal blank and comprises a flat approximately rectangular body portion 16 having a longitudinal slot 17 therein, the blank at one end of the body portion being bent to provide a right angularly extending portion 18 which in turn is bent to provide clip fingers indicated by the numeral 19, the fingers being formed by providing a slot 20 in the blank extending inwardly from the outer ends of the fingers and part way of the width of the portion 18. Each of the fingers has its end portion bent back upon itself as indicated by the numeral 21 so that the ends of the fingers are adapted to engage the cross piece 7 of the guard bridge of one of the valves of the instrument as

clearly shown in Figures 1 and 2 of the drawings, the branch 8 from the said cross piece extending through the slot 20 between the overturned outer ends of the fingers as clearly shown in the said figures. Preferably the attaching clip is formed from resilient metal so that the overturned ends of the clip fingers may be proportioned to snugly engage the cross piece 7 of the guard bridge, and it will be evident at this point that the engagement of the said ends of the fingers with the cross piece of the guard bridge will effectually prevent any inward or outward displacement of the clip with respect to the guard bridge as well as any upward or downward displacement. The numeral 22 indicates a clamping bar which is arranged longitudinally of the inner side of the body member 14 of the rest and this bar is provided near its ends with openings for the reception of the threaded ends of bolts 23 fitted through openings 24 formed in the body member 14 of the rest. One of the bolts 23 engages also through the slot 17 in the attaching portion 16 of the attaching clip and it will now be evident that by tightening the bolt, after the clip member has been properly adjusted, the said attaching portion of the clip member will be securely clamped between the respective end of the clamping bar 22 and the flat inner face of the body 14 of the rest so that the adjustment is maintained.

The other attaching clip is most clearly shown in Figures 3 and 4 of the drawings and this clip is likewise formed from a blank of resilient sheet metal and comprises an attaching portion 25 having a longitudinal slot 26 therein and an extension 27 at one end which corresponds to the portion 18 of the clip 15 but is preferably somewhat longer due to the relative disposition of the valves to the guard bridges of which the rest is attached. The portion 27 of the attaching clip 25 has its outer portion bent outwardly at right angles to provide clip fingers 28 separated by a slot 29 extending between the fingers and longitudinally of the portion 27 of the clip member, and these fingers 28 are bent back upon themselves as at 30 to provide portions 31 spaced from the first mentioned portions of the fingers, these latter portions being in turn sharply bent back upon themselves as at 32 so as to provide finger pieces 33 which extend outwardly beyond the bends 30 and the outer ends of which may be deflected in an outward direction as clearly shown in Figures 2 and 3 of the drawings. It will be evident by reference to Figures 1, 2 and 4 of the drawings that the attaching clip 25 shown in these figures and in Figure 3 is secured by the other one of the bolts 23 and the other end of the clamping bar 22 and by reference to Figures 1 and 2 it will be evident that the portions 28 and 31 of the clip fingers are designed to engage and partly

embrace the cross piece 7 of the guard bridge of the respective valve, the branch 8 from the said cross piece of the bridge as well as its extension 9 engaging in the slot 29 of the 5 clip member. At this point it will be evident that in applying the rest attachment to the instrument, the clip fingers 19 of the clip member 15 are first engaged with the cross piece 7 of the guard bridge for one of the 10 valves as shown in Figure 2 whereupon two fingers of the right hand may be engaged with the finger pieces 33 of the clip fingers of the clip member 25 and this member, due to its inherent resiliency, sprung in an outward 15 direction and disposed in such position that when released its clip fingers will engage with the cross piece 7 of the guard bridge of the other valve and thus complete the attachment of the device to the instrument. As in the case of the attaching clip 15, the clip 25 is designed to snugly engage the members of the guard bridge and in such a manner as to insure against inward or outward displacement of the clip member or an up or down 20 displacement thereof. It will therefore be evident that in a moment's time the rest attachment may be applied to or removed from the instrument and it will likewise be evident that when the attachment is in place it will 25 be firmly and securely held against any displacement whatsoever and will therefore serve its purpose in a most effective manner. It will also be evident by reference to Figure 30 2 that the rest is supported in such spaced relation to the operating parts of the valves of the instrument as to effectually preclude any contact of the parts with the clothing of the player.

It will be observed that each of the attaching clips is held in place and in positions of adjustment through the medium of a single one of the bolts 23 so that, as will be observed by reference to Figure 1, the attaching portion of the clip may be pivotally as well as 40 shiftably adjusted between the ends of the clamping bar 22 and the flat inner face of the rest body 14 and consequently the members may be caused to assume any desired positions of adjustment so as to adapt the said clip members for engagement with the guard bridges of two of the valves of the instrument regardless of the relative disposition of the 45 said guard bridges.

Figures 6, 7 and 8 of the drawings illustrate a slight modification of the invention which may be resorted to where found desirable and in these figures the body of the rest attachment is indicated by the numeral 34 and is supported at one end by a clip member 35 which is identical with the clip member 15 hereinbefore described and illustrated in Figure 5. The other attaching clip member is indicated by the numeral 36 and is of a somewhat different construction. This latter clip member comprises an attaching por-

tion 37 which is of rectangular form and provided with a relatively shallow rectangular sleeve portion 38 which is of a depth slightly greater than the thickness of the clamping bar 22 so that the sleeve portion is adapted 70 to be readily fitted onto one end of the said clamping bar. Likewise the sleeve is internally of a width considerably greater than the width of the clamping bar which in these figures is indicated by the numeral 39, so that the clip member 36, when its sleeve member is fitted to the bar, is capable of angular as well as sliding adjustment with respect to the bar thus permitting freedom of adjustment of the said member to the same extent 75 as the corresponding attaching clip member 25 in the first described embodiment of the invention. The attaching clip member 36 comprises, in addition to the body portion 37, and its integral sleeve, a right angular 80 extension 40 which terminates in clip fingers 41 corresponding to the fingers 28 and terminating in finger pieces 42 corresponding to the finger pieces 33.

From the foregoing description of the invention it will be seen that there is provided a rest attachment for saxophones so constructed and adapted to be so applied to the instrument as to prevent interference of the clothing of the player with the operation of 90 the lowermost valves and while the invention is illustrated as adapted primarily for application to a saxophone, it will be understood that the principles thereof may find embodiment in attachments for use in connection 95 with other valved wind musical instruments. It will also be understood that notwithstanding the different relative arrangement of the lowermost valves in the different types of 100 saxophones referred to above, either embodiment of the invention is readily applicable to the several types. It will also be evident that if desired the attachment may be placed on the market in condition comprising the rest proper, including the clamping bar 22 and the clip member 15 together with one of the clip members 25 and one of the clip members 36 inasmuch as the members 25 and 36 are adapted to be readily substituted one for the other.

It is to be understood, of course, that various changes may be made, within the scope of what is claimed, without departing from the spirit of the invention.

Having thus described the invention what I claim is:

1. The combination with a valved wind musical instrument of the saxophone type including the usual valves, of a rest position in outwardly spaced relation to one of the 125 valves and constituting a guard therefor.

2. The combination with a valved musical instrument of the saxophone type including the usual valves and guard bridges for the valves, of a rest, and resilient clip members 130

- carried thereby for attachment to said bridges.
3. The combination with a valved musical instrument of the saxophone type including the usual valves and guard bridges and which bridges include the usual cross pieces and branches extending therefrom, of a rest, and resilient clip members carried by the rest and having clip fingers for engagement with the cross pieces of the guard bridges and straddling the branches thereof.
4. A rest attachment for wind musical instruments of the saxophone type comprising a rest body, and attaching clip members adjustably mounted upon the body for engagement with the valve guard bridges of the instrument.
5. A rest attachment for wind musical instruments of the saxophone type comprising a rest body, and attaching clip members pivotally and slidably adjustably mounted upon the body for engagement with the valve guard bridges of the instrument.
6. A rest attachment for wind musical instruments of the saxophone type comprising a rest body, an attaching clip member mounted upon the body near one end thereof, a resilient clip member adjustably mounted upon the body near the other end thereof, and means for retaining the last mentioned clip member in positions of adjustment.
7. A rest attachment for wind musical instruments of the saxophone type comprising a rest body, an attaching clip member mounted upon the body near one end thereof, an attaching clip member mounted upon the body near the other end thereof for pivotal and shifting adjustment and including a pair of resilient clip fingers, and means for holding the last mentioned clip member in positions of adjustment.
8. A rest attachment for wind musical instruments of the saxophone type comprising a rest body, a clamping bar at one side of the body, means for adjusting the bar in the direction of the body, and attaching members having attaching portions disposed between the bar and the said side of the body whereby to be clamped in positions of adjustment.
9. A rest attachment for wind musical instruments of the saxophone type comprising a rest body, a clamping bar at one side of the body, bolts fitted through the body and adjustably threaded into the clamping bar and constituting means for adjusting the bar in the direction of the body, and attaching members having attaching portions disposed between the bar and the said side of the body.
10. A rest attachment for wind musical instruments of the saxophone type comprising a rest body, a clamping bar at one side of the body, bolts fitted through the body and adjustably threaded into the end portions of the clamping bar, and attaching clip members having attaching portions disposed between the bar and the said side of the body and each having a slot therein to accommodate the respective bolts, the said clip members being adjustable pivotally about the respective bolts and shiftably with respect to the same and the said body, and the said bolts constituting means for adjusting the bar to clamp the attaching portions of the attaching clips in positions of adjustment.
11. A rest attachment for wind musical instruments of the saxophone type comprising a rest body, a clamping bar at one side of the body, means for adjusting the bar in the direction of the body, an attaching clip at the said side of the body near one end of the bar and retained thereby, and an attaching clip at the said side of the body near the other end of the bar having a sleeve portion fitting the bar in a manner to provide for angular and shifting adjustment with respect to the bar.
12. The combination with a valved wind musical instrument of the saxophone type including the usual valves, of a rest supported by the instrument and positioned for engagement with the body of the player to constitute a guard to prevent contact of the valves of the instrument with the player's body or clothing.

In testimony whereof I affix my signature.

FRANK L. GESFORD.
